UNITED STATES PATENT OFFICE.

EDGAR B. NICHOLS, OF ROCHESTER, NEW YORK, ASSIGNOR TO AMERICAN FLYER MFG. CO., OF CHICAGO, ILLINOIS, A CORPORATION.

PROCESS OF PRODUCING COMPLEMENTAL PARTS.

Application filed March 14, 1921. Serial No. 452,375.

To all whom it may concern:

Be it known that I, EDGAR B. NICHOLS, a citizen of the United States of America, residing at Rochester, in the county of Monroe 5 and State of New York, have invented certain new and useful Improvements in Processes of Producing Complemental Parts, of which the following is a full, clear, and exact specification.

10 This invention relates to the manufacture of complemental metal plates, and has for its object to provide a process by which such plates can be produced from a single sheet of material without excessive cost, by which 15 the desired fit between the several parts can be easily and accurately secured, and by which a substantial saving of metal will be effected.

It is a well known fact that where a blank 20 is punched from sheet metal it can only be replaced in its original position by the application of considerable pressure, assuming that the blank can be properly located relative to the plate from which it was cut. 25 Moreover it is difficult to mechanically change the dimensions of one of the parts a few thousands so that they will fit together either loosely or tightly as desired. At the present time sheet metal parts which are 30 complemental in the sense that they are combined together to form the cooperating parts of one unit, such as the halves of a hinge joined by a pintle, or a punch and die, are made separately, necessitating the use of 35 tools for each part. If a single tool is used to cut the parts from a sheet of metal they must be carefully fitted by hand, as by filing or mechanically obtaining the desired clearance between the parts. This is expensive 40 and unless very carefully done, inaccurate. I have successfully produced parts which cooperate from a single sheet of metal with the use of a single punch and die, by obtaining the desired working clearance be- 45 tween the several parts by etching. This is a cheap and accurate method which requires but little time and no skilled labor. While my invention is applicable to a large number of uses, I will describe by way of illustration, its use in making a light punch and die such as is shown in my application for patent, Serial No. 345,429, filed December 16th, 1919. My present invention is particularly useful in making such punches in 50 quantity. As illustrating the general ap-

plication of my invention to the making of complemental metal parts I have also shown a hinge as a second embodiment, and a floor plate as a third.

Coming now to the drawings, in which like reference characters denote like parts throughout:

Fig. 1 is a plan of a metal blank for making a punch in accordance with, and illustrating the first embodiment of my invention:

Fig. 2 shows the same blank with one complemental part punched therefrom;

Fig. 3 is a perspective of the blank bent to form a punch, showing the assembling of the complemental parts;

Fig. 4 is a perspective of the completed punch and die;

Fig. 5 is a perspective showing a number of parts held by a rod for etching;

Fig. 6 is a fragmentary elevation of parts ready for etching;

Fig. 7 is a section through a tank of etching solution, with parts suspended therein;

Fig. 8 is a plan of a metal blank from which the complemental parts of a hinge are made in accordance with, and illustrating a second embodiment of my invention;

Fig. 9 is a plan of the complemental parts cut from the sheet metal;

Fig. 10 is an end elevation of the parts of the hinge and the hinge pintle;

Fig. 11 is a perspective of the completed hinge;

Fig. 12 is a plan of a floor plate blank;

Fig. 13 is a plan of the completed floor plate lock; and

Fig. 14 is a side elevation of a number of parts held by a clamp for etching.

As shown in Figs. 1 to 6 inclusive, I illustrate a light paper punch made in accordance with my invention. The complemental parts here are the punch, or male die, and the die, or female die. This punch is made from sheet or strip metal, and as shown in Fig. 1 blanks 1 are first cut out. With a punch shaped as shown in dashed lines at 2 in this figure the star 3 is punched from the blank 1 leaving the female die 4. The blank is then folded upon the dashed line 100 Fig. 2 and the ends 5 and 6 are temporarily held by a clamp C. The punchings or stars 3 are perforated at 7, preferably before being cut from the metal, this aperture being convenient for stringing them upon a hanger 110

H, by which they are suspended in a tank T filled with an etching bath E. In Fig. 5 a series of parts 3 are shown upon a hanger. If desired these parts can be left unperforated and held by a clamp 40 as shown in Fig. 14. In Fig. 6, I show the stars 3 as having their sides covered with an acid resisting coating 8', such as wax. In practice, however, I do not find this coating essential. 10 After etching the male die 3 until its periphery is sufficiently reduced, the star is placed in the female die 4, and, with the ends 5 and 6 clamped as in Fig. 3 the male part 3 is fastened to the end 6 in any suitable manner. Although the parts may be sweated together, I prefer to spot weld them, this being indicated by shading at 8. The dimension of the slot between the male and female dies is exaggerated in scale for 20 the sake of clearness. Fig. 4 shows the completed punch with the complementary parts 3 and 4 made from a single piece of metal, and also by the use of a single punching.

25 In the above described embodiment of my invention I have found that where the blank is made of cold rolled steel of approximately .040" thick, that a clearance of .005" between two edges of the cooperating complementary parts 3 and 4 produces the desired working fit for paper cutting. To etch off this amount I first clean the parts with gasoline or benzine and then immerse them in a bath consisting of 4 parts of nitric acid to 35 one part water. By trial a table can be readily computed which will indicate the reduction per minute. I have found that the time may vary considerably with changing conditions.

I have shown a hinge as illustrating a 40 second article having cooperating complementary parts, illustrating this embodiment in Figs. 8 to 11, inclusive. Here a metal plate or strip 13 is cut into parts by a single punching. The die should be shaped as 45 shown in the shaded portion at 16, roughly E shaped, so that by cutting every other space or by stamping out the E shaped portions shown in dashed lines, a series of complementary parts, 14 and 15, will be formed.

50 Screw perforations 18 are preferably first punched in the metal, although this operation can be done simultaneously with the blanking. The parts 14 and 15 can be joined by a pintle 21 after one section is etched 55 and the pintle seats are rolled up as shown at 22 and 23, Fig. 10. I, therefore, suspend one section of the hinge in an etching bath reducing the edges 24 of the pintle seats 23 until the parts cooperate with the 60 desired freedom of movement.

As a third embodiment I show a floor plate 30 and connection 31 such as are commonly used in gymnasium floors for support-

ing apparatus stays. The plate 30 is formed from sheet metal, and a punch cuts out a complementary part 31. This part (or the plate 30) is suitably etched in acid until the dimensions of the complementary parts are such that part 31 forming a locking bar, can readily be thrust through the aperture 32. 65 A stay wire 33 is anchored to part 31, so that by entering and turning part 31 in plate 30 the stay can be securely held under tension. The plate 30 is preferably sunk in the floor 35, so as to be flush therewith, the floor having a cut away portion 36 in which the locking bar 31 can turn.

Having thus described my invention what I claim as new and desire to secure by Letters Patent is:

1. The process of producing cooperating complementary parts from a single piece of sheet metal which consists in stamping one part from the other, etching a cooperating edge of at least one of the parts, thereby 85 producing the desired clearance between the several parts.

2. The process of making cooperating complementary parts from a single piece of sheet metal which comprises stamping one part 90 from the other, and securing the desired fit between the edges of the cooperating parts thus formed by etching.

3. The process of producing complementary parts of sheet steel which consists in striking one part from the other, changing a dimension of at least one of the cooperating edges of the complementary parts by suspending it in a solution of nitric acid and water until the desired fit is secured.

4. The process of making complementary metal parts for a punch and die which comprises stamping the male punch from the female die, etching the edges of one of the parts until the two parts will cooperate with the desired fit.

5. The process of making complementary metal parts for a punch and die which consists in stamping the punch from the die, and causing the parts to cooperate by changing the dimensions of one of them to a predetermined degree by etching.

6. The process of constructing complementary metal parts for a punch and die from sheet metal which comprises the following 115 steps; first, punching the male punch from the sheet metal, thus leaving the female die; and second, etching the periphery of the male die, reducing the dimensions thereof to a predetermined degree; whereby a smooth 120 working fit will be secured between the several parts.

Signed at Rochester, N. Y., this 5th day of March, 1921.

EDGAR B. NICHOLS.
